UNITED STATES PATENT OFFICE

KARL FRIEDRICH UNGERER, OF PFORZHEIM, GERMANY

STRAIGHTENING AND ROLLING MACHINE

Application filed December 20, 1928, Serial No. 327,241, and in Germany December 27, 1927.

This invention relates to a straightening and rolling machine.

The straightening rolls of the modern straightening machines are so thin that, for obtaining a good straightening result, they must be forced more or less strongly towards the material to be straightened by part stretchings of the material to be straightened by means of adjustable supporting elements.

Such thin straightening rolls are open to the objection that they yield when working as if they were not supported on their entire length. This supporting has hitherto been effected by mounting the straightening rolls in their whole length in troughs, from which the surface of the straightening rolls projects just sufficiently for straightening the plate passing thereover. As the straightening is carried out at a high pressure, the frictional resistance naturally increases in the trough bearings in proportion to the length of the straightening rolls and the width of the plate to be straightened.

The object of this invention is, to effect a reduction of this frictional resistance or to transform the so-called sliding-friction into rolling friction, at the same time allowing advantageous sagging of the straightening rolls towards the material being straightened.

The novelty consists in that the rolls of the stretching machines or of the rolling mills are supported on surfaces, over which they roll during the straightening or rolling operation.

An embodiment of the invention is illustrated by way of example in the accompanying drawings in which:

Fig. 1 is a side elevation showing the improved straightening machine without pinion and rack for driving the straightening rolls.

Fig. 2 is a section on line 2—2 of Fig. 1.

Fig. 3 shows in top plan view the lower machine frame with lower supporting surface.

Fig. 4 shows in side elevation and

Fig. 5 in top plan view the coupling point of the roll frames in section on line 5—5 of Fig. 4.

Fig. 6 shows in top plan view the device

for adjusting the supporting irons arranged on the supporting yoke.

The under frame *a* of the machine forms a perfectly plane supporting surface *a'* for the lower straightening rolls *b*. Two offset portions *a₂* are provided on the base frame of the machine in which the supporting bearings *a₃* for the supporting columns *c* of the supporting yoke *d* are mounted (Fig. 2).

The latter serves for supporting the upper straightening rolls. The upper as well as the lower straightening rolls *b*, *e* respectively are mounted each independently in a transportable frame *b₁*, *e₁* respectively. The lower frame *b₁* is guided by means of rollers *b₂* on the lower machine frame *a*, the upper frame *e₁* being suspended by means of rollers *e₂* on the supporting yoke *d*. The two frames *b₁* and *e₁* are connected with each other by a transverse shaft *f* so that they carry out together the shifting movements in the direction of the arrow line A necessary for the straightening of the sheet metal passing through between the straightening rolls *b* and *e*.

The connection of the lower roll frame *b₁* with the upper roll frame *e₁* is effected by means of the shaft *f*. This shaft is mounted in the bearings *e₃* of the forks *e₄* of the upper frame *e₁*. An eccentric *f₁* is keyed on the shaft *f* between the forks *e₄*. Two prongs *b₅* project from the lower straightening roll frame *b₁* and bear one on each side of the eccentric *f₁*. Consequently every movement in the direction of the arrow A (Fig. 1) performed by the straightening roll frame *b₁* is imparted to the upper straightening roll frame *e₁*, the motive force being transmitted from the prongs *b₅* to the eccentric *f₁* and from this latter to the shaft *f* and from the shaft *f* to the forks *e₄* and thus to the upper straightening roll frame *e₁*.

The lower and upper straightening rolls *b*, *e* respectively carry on the end projecting from the frames *b₁*, *e₁* respectively a pinion *b₃*, *e₃* respectively, said pinions being displaced in the horizontal plane so that they gear freely

with a rack *g*, *h* respectively, fixed on the one offset portion *a₂* of the lower machine frame and on the supporting yoke *d* respectively, said racks being of double the width of

the pinions b_3, e_3 respectively. The lower and upper straightening rolls b, e are thus forced to roll on the supporting surfaces a_1, d_1 respectively during the shifting movements of the frames b_1, e_1 respectively. The shifting movements of the roll frames b_1 and e_1 in the direction of the arrow line A are effected by means of spur wheels i_1 mounted in the lower machine frame a . The spur wheels i_1 , receive their drive through the intermediary of pinions mounted on the projecting ends of the main driving shaft i , which is also journaled in the lower machine frame a . Between these pinions, towards the middle of the main driving shaft i , a large toothed wheel is mounted with which the driving pinion of a reversible electric motor x meshes. The reciprocating movement of the straightening rolls b and e in the direction A is effected simply by reversing the poles of the electric motor. Evidently it would also be possible to change the direction of rotation of the shaft i and consequently the movement of the straightening rolls b and e by other means, for example a belt reversing gear, such as is employed for example on planing machines for the reciprocating movement of the planing table.

For the purpose of straightening, the end edge of the sheet is clamped between the upper and lower rolls b and e situated on the left end of the rows of straightening rolls (Fig. 1). The instant the two rows of rolls commence their common travel over the supporting surfaces a_1 and d_1 , the sheet will be pulled more and more between the rows of rolls in exactly the same manner as on a known sheet straightening machine with stationary straightening roll bearings. The sheet travels therefore as in the known sheet straightening machines between the two rows of straightening rolls and finally drops on to the table plate u . The rows of straightening rolls b and e have thereby travelled from the left to the right end of the supporting surface. If a single pass through the machine is insufficient to straighten the sheet, the other end of the sheet is fed from the table plate u between the upper and lower rolls b and e , this time however those on the right end of the rows of straightening rolls (Fig. 1), after which the return travel of the rows of rolls commences, during which the sheet again travels between the rows of straightening rolls, but this time in the opposite direction and finally, providing no table plate u is provided on the left end of the rows of straightening rolls, drops on the floor at the instant, at which the rows of straightening rolls have reached their initial position shown in Fig. 1. Whilst the sheet is travelling through the machine it must evidently not be held in any manner, but must be left absolutely free for the conveying caused by the straightening rolls.

The straightening rolls b, e respectively supported over their entire length are adjusted with regard to their supporting faces a_1, d_1 respectively by the oscillation of the journals b_6, e_6 respectively which carry the rollers b_2, e_2 respectively and are journaled so that they can oscillate eccentrically in the frames b_1, e_1 respectively in such a manner that these rolls b, e as well as the rollers b_2, e_2 bear permanently against their supporting surfaces.

The distance between the upper and lower rows of straightening rolls b and e is adjusted by lifting and lowering the supporting yoke d . With this object in view the supporting yoke is supported by means of spiral springs k on the columns c , the upper portions of said columns being constructed like screw spindles c_1 . The lifting and lowering of the supporting yoke d is effected by rotating the worm wheels l , the hubs l_1 of which form nuts, and through the intermediary of worms m' on the two shafts m . The shafts m , driven by a common hand wheel m_2 arranged so that it is easily accessible, are connected with each other by suitable means, for instance by a feed chain n so that all hubs or nuts l_1 are rotated simultaneously.

Central portions of the sheet metal plate can be stretched by bending through the upper row of straight rolls e towards the material to be straightened. With this object in view the upper straightening rolls e are supported on the supporting yoke d not directly but through the intermediary of irons d_2 forming the upper supporting surface d_1 . The irons d_2 have the shape of oblong wedges, the inclined plane of which bears shiftably against a corresponding inclined plane d_5 (see Fig. 1) of the supporting yoke d and which end at both ends in fingers d_3, d_4 respectively, by means of which they are suspended on transverse rods o, o_1 fixed in the supporting yoke d . The upper supporting surface d_1 formed by the irons d_2 can become curved towards the straightening rolls e by pushing on the inclined plane of the supporting yoke d the extreme irons. This is effected by means of a screw spindle p which has a hand wheel p_1 on one end and is threaded through a nut p_2 fixed on the supporting yoke d , said screw spindle adapted to act, through the intermediary of a U-shaped intermediate element p_3 , upon blade springs q extending transversely over the end faces of the fingers d_3 and fixed on the supporting yoke d so that they can be bent more or less strongly with regard to the end faces of said finger d_3 . As the height of the bending curve of the blade springs q increases from the two sides towards the middle, the central irons d_2 are pushed on the inclined plane of the supporting yoke d a greater distance than the extreme irons, whereby to the upper supporting surface d' a curve transversely to the

direction of the arrow A and directed towards the straightening rolls *e* is given. By this curve extending over the entire supporting surface the upper straightening rolls *e* are supported also in the bent state over their entire length.

The end faces of the fingers *d*₄ of the irons *d*₂ bear also against blade springs *q*₁ which are thereby, at the shifting of the irons *d*₂, 10 also curved in a curve congruent to the curve at which the blade springs *g* are bent.

If the irons *d*₂ are pushed back so far that the blade springs *g* and *g*' are straight, the supporting surface *d*' is plane. To bring 15 back the irons *d*₂ into their normal position the screw spindle *p* has to be screwed back. In order to keep the irons *d*₂ in contact with the stretching blade spring *q* they are either suspended on the same or the opposite blade 20 springs *q*' are selected of such strength that they push back the irons *d*₂. The returnings of the irons *d*₂ might however be effected by a screw spindle acting upon the blade springs *g*' and positively rotated together with the 25 screw spindle *p* or by other suitable means so that the blade springs *g* and *g*' are permanently in the same position.

In the ordinary straightening the lower and upper straightening rolls *b* and *e* are 30 mutually displaced. In order to increase the stretching effect of the rolls, as will be sometimes necessary in the straightening of badly rolled sheet metals, it is advisable to bring the rolls into register with each other for one 35 or two passes of the material to be straightened. The rolls exert in this position a true rolling pressure upon the material producing the equalizing stretching. The point at which the lower and upper roll frames *b*₁ and *e*₁ are

40 coupled is constructed in such a manner that, according to requirements, the rolls *b* and *e* may be mutually displaced or brought into register with each other. With this object in view an eccentric *f*₁ is fixed on each end of 45 the transverse shaft *f*, the circumference of said eccentric fitting accurately between two arms *b*₅ of the lower frame *b*₁, said arms engaging with a fork *e*₄ of the upper frame *e*₁. The eccentrics *f*₁ situated between the eyes 50 *e*₅ of the fork *e*₄ and bearing against the sliding faces of the arms *b*₅ can be rotated at the same time on both sides of the frames *b*₁ and *e*₁ 180° in the direction of the arrow B (Fig.

4) by means of the transverse shaft *f* rotatably mounted in the eyes *e*₅. The centres of the lower and upper straightening rolls *b* and *e* are thereby brought accurately the one over the other.

In order that the sheet metal plate to be 60 straightened is delivered plane from between the rolls, the undulated gap formed between said rolls can enlarge towards the one delivering end or towards both ends. This may be obtained, as shown in Fig. 4, for instance 65 by making the extreme rolls *e* thinner. The

pinions *e*₃ are then omitted for these thinner rolls *e*, as otherwise the circumferential speed of the inner rolls would be different from the speed of the sheet metal plate conveyed by the other rolls *e*. The lower rolls *b* are however all of the same diameter and their pinions *b*₃ remain in gear with the rack *g*, and they convey the straightening material to the delivering end. The journal holes for the thinner rolls *e* are displaced towards the upper supporting face *d*₁ so that also the extreme delivering rolls are in touch with the upper supporting surface.

Wire brushes *r*, arranged between the lower straightening rolls *b* serve for removing the hammer scale and the like, the ends of said wire brushes being mounted in slots *s* of the lower roll frame *b*₁ and said brushes bearing under the action of the gravity against the lower supporting surface *a*₁. The hammer scale drops into the slots *t* of the lower supporting surface, said slots extending obliquely to the direction of movement A of the rolls. One brush *r* may be arranged between every two lower straightening rolls *b*.

A sheet metal plate can be straightened only by passing completely through between the rows of straightening rolls *b* and *e*. The supporting surfaces *a*₁ and *d*₁ must therefore be at least as long as the longest plate to be straightened plus double the total length of the whole lower row of rolls *b*, which is always the longer one of the two rows of rolls.

In order to prevent the delivered straightened sheet metal from dropping, a table plate *u* may be arranged on one delivering side or on both delivering sides of the lower frame *b*₁, said table frame resting on brackets *v* fixed on the end face of the frame *b*₁.

Any desired number of rolls *b* and *e* may be provided. If in an upper and lower frame only one roll is journaled in each frame, these frames form a rolling mill which, if the rolls are very thin, exerts a very good stretching action.

I claim:

1. A straightening and rolling machine comprising in combination with the upper and lower straightening or rolling rolls, an upper supporting surface, and a lower supporting surface over which said rolls roll during the straightening and rolling operation.

2. A straightening and rolling machine as specified in claim 1, comprising in combination an upper row of straightening and rolling rolls, a lower row of straightening and rolling rolls, an upper supporting surface, and a lower supporting surface over which said rolls roll.

3. A straightening and rolling machine as specified in claim 1, comprising in combination with a lower row of rolls and with an upper row of rolls, a lower supporting surface formed by the lower machine frame, a

supporting yoke forming an upper supporting surface, and means for adjusting the distance between said upper supporting surface and said lower supporting surface.

5 4. A straightening and rolling machine as specified in claim 1, comprising in combination, a lower machine frame forming a lower supporting surface, a supporting yoke forming an upper supporting surface, means

10 for adjusting the distance between said yoke and said under frame, a frame suspended in said yoke, a frame guided in said lower machine frame, a row of straightening rolls journaled in said lower frame, a row of

15 straightening rolls journaled in said upper frame so that said rows of rolls bear against the corresponding supporting surface, means for coupling said frames with each other, and means for shifting said frames simultaneously.

20 5. A straightening and rolling machine comprising in combination a lower machine frame forming a lower supporting surface, a supporting yoke forming an upper supporting surface, means for adjusting the distance between said upper supporting surface and said lower supporting surface, a frame suspended in said yoke, a frame guided in said lower machine frame, a row of straightening rolls journaled in said lower frame, a row of straightening rolls journaled in said upper frame, a rack on said lower frame, a pinion on the corresponding end of each roll of said lower row of straightening rolls 25 meshing with said rack, a rack on said supporting yoke, a pinion on the corresponding end of each roll of said upper row of straightening rolls meshing with said rack, and means for shifting to and fro said frames simultaneously said rolls rolling on the corresponding supporting surfaces.

30 6. A straightening and rolling machine as claimed in claim 5, comprising a lower supporting surface formed by the lower machine frame having apertures through which the hammer scale drops.

35 7. A straightening and rolling machine as claimed in claim 5, comprising in combination a lower row of rolls, a lower supporting surface formed by the lower machine frame having slots through which the hammer scale drops said slots extending obliquely to the direction of movement of said rolls.

40 8. A straightening and rolling machine 45 as claimed in claim 5, in which the upper supporting surface on said supporting yoke having an inclined lower surface consists of irons each in the shape of a flat wedge the inclined plane of which bears against the inclined lower surface of said supporting yoke, and means for shifting said irons on said supporting yoke to form a downwardly directed curve in said supporting surface.

45 9. A straightening and rolling machine 50 as claimed in claim 5, in which the upper sup-

porting surface on said supporting yoke having an inclined lower surface consists of irons each in the shape of a flat wedge the inclined plane of which bears against the inclined lower surface of said supporting yoke, blade springs bearing one against each end of said wedge shaped rows, and means for bending one of said blade springs to shift the corresponding irons on said inclined surface of said supporting yoke to form a curved supporting surface.

55 10. A straightening and rolling machine as specified in claim 5, comprising in combination with the lower rolls and the upper rolls, a supporting frame for said lower rolls, a supporting frame for said upper rolls, and means for mutually shifting said roll supporting frames half the distance between the centres of two rolls so that said rolls may be adjusted to the straightening position and to the true rolling position respectively.

60 11. A straightening and rolling machine as specified in claim 5, comprising in combination with the lower rolls and the upper rolls, a supporting frame for said lower rolls, a supporting frame for said upper rolls, a shaft journaled in said upper roll frame, an eccentric on said shaft, and two vertical arms projecting upwardly from said lower roll frame said eccentric bearing against the vertical inner sides of said arms so that said roll frames are mutually shifted half the distance between the centres of two rolls so that said rolls may be adjusted to the straightening position and to the true rolling position respectively.

65 12. A straightening and rolling machine as specified in claim 5, comprising in combination with the lower supporting frame having vertical slots, a row of lower straightening rolls, wire brushes one between every two lower rolls extending transversely over the lower supporting surface and loosely guided in said slots so that they are pressed by gravity against said lower supporting surface.

70 13. A straightening and rolling machine as specified in claim 5, comprising in combination the lower machine frame, brackets fixed on the end of said lower machine frame, and a table plate on said brackets adapted to receive the sheet metal plate delivered from the machine,

75 14. A straightening and rolling machine as specified in claim 5, in which the end rolls in the upper row of straightening rolls and in the lower row of straightening rolls are of smaller diameter than the middle rolls so that the gap between the two rows of rolls is enlarged towards the ends.

80 15. A straightening and rolling machine as specified in claim 5, comprising in combination with the upper and lower supporting surfaces, an upper row of straightening rolls and a lower row of straightening rolls the end rolls in said rows being of smaller diam-

70
